UNITED STATES PATENT OFFICE.

QUINCY L. FLARIDA, OF DAYTON, OHIO.

METALLIC FENCE-POST.

1,170,230.

Specification of Letters Patent.

Patented Feb. 1, 1916.

Application filed March 6, 1915. Serial No. 12,480.

To all whom it may concern:

Be it known that I, QUINCY L. FLARIDA, a citizen of the United States, residing at Dayton, in the county of Montgomery and State of Ohio, have invented certain new and useful Improvements in Metallic Fence-Posts, of which the following is a specification, reference being had therein to the accompanying drawing.

- 10 This invention relates to a sheet metal fence post, and the object of the invention is to provide a strong, durable post which can be produced at a low cost; and to provide such a post with wire-supporting devices which will receive the wire and retain the same in position without bending of the parts, and which will be so arranged that they will not materially weaken the post.
- 20 In the accompanying drawings Figure 1 is a side elevation of a fence post embodying my invention; Fig. 2 is a vertical sectional view of such a post; and Fig. 3 is a cross section of the same.

25 In these drawings I have illustrated one embodiment of my invention and have shown the post as a whole at 1. The post is made from sheet metal, preferably by taking a sheet of metal of the proper length 30 and width and bending the same into triangular form with the longitudinal edges of the sheet arranged adjacent one to the other near the middle of one face thereof. Preferably, these edges are spaced a short 35 distance apart to form a slot 2 through which staples or other wire-fastening devices may be driven. It will be noted that the two sides of the post converge away from the wire-supporting face thereof and 40 are thus arranged edgewise to oppose any strain which may be imposed upon the post by the fence. The post is further strengthened by the use of transverse corrugations 3, these being provided usually by forming 45 the post from corrugated metal with the corrugations running transversely of the sheet. A triangular post provided with these transverse corrugations is very strong, being equal to, if not superior to, a round 50 post in strength, and has the advantage over the round post of being easier to manufacture. A sheet of metal can be bent into triangular form with less trouble and expense than it can be bent into cylindrical 55 form. These posts are frequently filled with some suitable substance such as a wooden

core or plastic material. Where the post is filled with a plastic material the corrugations also serve to prevent the longitudinal displacement of the filler. It is also desirable that a post of this type should be provided with wire-supporting devices to support the wires at the proper height. In the present device I have provided the post with a vertical series of wire-supporting 60 devices, the several devices being arranged comparatively close together so that the wires can be supported at any desired height and spaced apart as desired. Further, I have so constructed the supporting 65 devices that the wire can be placed therein without the use of tools or the necessity of bending the supporting devices, and when once inserted will be retained therein. To this end each supporting device comprises a 70 lip or projection 4 struck from the wire-supporting face of the post, extending upwardly, and having its upper end spaced away from the face of the post. Arranged adjacent to this lip is a downwardly extending lip or projection 5, also struck from the face of the post, and overlapping the lip 4. The lip 5 has its lower end spaced away from the face of the post and, as here 75 shown, it is arranged close to the adjacent portion of the lip 4. The lip 5 is, however, of such a length that when pressed downward its lower end will not reach to the bottom of the lip 4. Consequently, by placing a wire back of the lip 4 and pressing 80 downward upon the same, the lip 5 may be caused to yield sufficiently to permit the wire to pass the end thereof and it will then spring into its original position, which will cause it to project above the wire and 85 effectively prevent the removal thereof. I prefer to place these fastening devices close to the edge of the sheet from which the post is formed and, as shown in the present drawings, I have struck the same from the 90 metal of the post along one side of the slot 2. When so arranged, the weakening of the post, which results from the striking out of the wire-supporting devices, is reduced to a 95 minimum.

100 It will be apparent from the foregoing description that I have produced a metallic fence post which may be manufactured at a low cost and which will have great 105 strength, and that I have provided this post with wire-supporting devices so arranged as to avoid materially weakening the post,

and that these wire-supporting devices are of such a character as to facilitate the attachment of the wire to the post.

While I have shown and described one form of the invention, I wish it to be understood that I do not desire to be limited to the details of construction shown and described, for obvious modifications will occur to a person skilled in the art.

Having thus fully described my invention, what I claim as new and desire to protect by Letters Patent, is:

1. A fence post formed of sheet metal and provided with a vertically arranged series of wire-supporting devices, said devices being spaced apart and each comprising an upwardly extending projection struck from the metal of said post and having its upper end bent outward away from the face of the post, and a downwardly extending projection also struck from the metal of the post alongside of and close to the upwardly extending projection and having its lower end bent outward away from the face of said post, said downwardly extending projection terminating above the lower end of the upwardly extending projection and being arranged to be engaged by a wire placed back of the upwardly extending projection and to yield to permit said wire to pass the lower end thereof.

2. A fence post formed of sheet metal having a longitudinal slot therein and hav-

ing a downwardly extending projection struck from the metal at one edge of the post and having an upwardly extending projection struck from the metal beyond and in close proximity to the first-mentioned projection, said projections overlapping and the first-mentioned projection having its lower end arranged close to the adjacent portion of the last-mentioned portion at a point between the ends of said last-mentioned projection and being yieldable to permit a wire to be forced past the end thereof and confined within the space between said projections and the body of the post.

3. A triangular fence post formed of a sheet of metal having its edges arranged close together near the center of one face thereof and having a series of wire-supporting devices struck from said face thereof along one edge of the sheet from which the post is formed, each of said devices comprising overlapping projections arranged side by side and in close proximity one to the other, one of said projections being yieldable to permit a wire to pass between the same and the other projection.

In testimony whereof, I affix my signature in presence of two witnesses.

QUINCY L. FLARIDA.
